Primary Examiner — Susan E Krakower(74) *Attorney, Agent, or Firm* — QuickPatents, Inc.; Kevin Prince**(57) CLAIM**

I claim the ornamental design for a suspension exercise apparatus, as shown and described.

DESCRIPTION

FIG. 1 is a perspective view of a suspension exercise apparatus, showing my new design;

FIG. 2 is a front elevational view thereof;

FIG. 3 is a top plan view thereof;

FIG. 4 is a left-side elevational view thereof, the right-side elevational view being a mirror image thereof;

FIG. 5 is a rear elevational view thereof; and,

FIG. 6 is a bottom plan view thereof.

The broken lines showing handles and a support chain in FIG. 1 depict environmental matter and form no part of the claimed design.
